MULTIPLE WEAVING LOOM

Christian Kiener, Epinal, France

Application July 14, 1949, Serial No. 104,760

Claims priority, application France July 27, 1948

3 Claims. (Cl. 139—18)

1

My invention has for its object a weaving machine incorporating a large number, say 20, of operative components forming as many elementary weaving units operating independently and assembled together to form, as a whole, a compound machine.

The main feature of this machine consists in that the weaving units are associated side by side and back to back on a common frame, said weaving units as designed for such an assembling operating each independently to make a fabric in a vertical plane, the weft being introduced through the passage of the shuttle over a horizontal reed that is held fast during this passage between the two sheets of subdivided vertically arranged warp, the shuttles being driven from stationary shuttle boxes.

Preferably the shuttle boxes are arranged two by two on a common support in side by side relationship so as to produce by reason of a corresponding shifting of the reeds and sheets of warp threads, an imbricating or overlapping of the different weaving units with reference to the two adjacent units between which they are held.

In each separate unit, the reed that is independent of the shuttle boxes executes a reciprocating rising and sinking movement so as to provide in its lowermost stationary position for the passage of the shuttle and in its upper position for the beating up of the weft against the fell of the cloth.

By reason of its novel features, my weaving machine shows numerous and considerable advantages. The bulk, the weight and the number of parts of the aggregate are considerably reduced for a machine incorporating a number of weaving units, when compared with the same number of looms arranged singly, the cost of erection is considerably reduced and the cost price of the machine is much lower than that of an equivalent number of single looms. The cost of the driving machine for such an arrangement is also greatly reduced as a single electric motor may control all the weaving units forming together the compound weaving machine. The transmission is considerably simplified and the consumption of power reduced. Lubrication is made much easier as a central lubrication system may be used for the system of elementary weaving units making up the machine and still further advantages will be apparent to any one skilled in the art.

Furthermore, the weaver may investigate at any moment for either side of the machine, and for all the separate units located on said side, that

2

is for one half of the total number of such separate units, the travel of the threads from the point from which the warp is wound off, up to the beaming of the fabric and also the sheets of warp threads of the weaving units are very near one another by reason of the overlapping of the said units so that consequently the weaver may repair a broken thread in any given elementary unit, start the latter again operating, inspect the resumption of the production of the fabric, and see to the operation of the warp beam without it being necessary for him to turn round the unit as in conventional looms. Again the sheets of warp threads being as stated very near one another by reason of the overlapping of the weaving units, the travel between the successive units will be equal to one half of the travel required heretofore. This will reduce finally the distances travelled over by the operator to a considerable extent.

The signalling of the stoppage required by the warp or by the weft or by mechanical mishaps may not only be executed in the usual manner on each weaving unit but it may also be provided centrally through electric means and appear on a single board for all the units forming the compound weaving machine. The centralising signalling boards of four machines may in fact be associated together at one end of said machines so as to allow them to be inspected by a person positioned at the intersection of two corresponding bays or rows of machines.

The automatic feeding of the weft to each weaving unit may be executed by incorporating to the latter a cop or shuttle changing device of any known or suitable type.

A further object of the invention consists precisely in automatically executing the feeding of the weft for the whole system of say 20 weaving units forming the compound machine. This object is achieved through the arrangement on each side of the compound machine of an upper conveyor receiving the full cops or shuttles, according as to whether the replacement of the weft is obtained through a change of cops or through a change of shuttles, from a central feeding station located at one end of the compound machine and ensuring the distribution to the shuttle or cop holders of the weaving units and further a lower conveyor adapted to receive the exhausted cops or shuttles that are thus collected.

According to a still further feature of the invention, the progression of the cops or shuttles on one hand and that of the exhausted

cops or shuttles on the other hand is ensured through the upper and lower strand respectively of one common conveyor.

The above-disclosed features and advantages and also further auxiliary features and advantages that have not yet been disclosed will appear clearly from the reading of the following description of a compound weaving machine executed in accordance with the invention and illustrated diagrammatically by way of a mere exemplification and by no means in a binding sense in accompanying drawings, wherein:

Fig. 1 is a plan view illustrating the general arrangement of my compound machine.

Fig. 2 is a corresponding elevational side view.

Fig. 3 is an end view of the machine.

Fig. 4 is an elevational side view of one of the weaving units together with a partial illustration of the two units between which it is mounted.

Fig. 5 is a plan view corresponding to Figure 4.

Fig. 6 is a partly vertical cross-sectional view of an automatic cop changing arrangement.

Fig. 7 is a corresponding plan view.

Figs. 8 and 9 are views similar to Figs. 6 and 7 respectively relating to an automatic shuttle-changing device.

Fig. 10 is an elevational side view of a distributor located at one end of the machine, and adapted to feed full cops on to a conveyor leading to the different weaving units on either or both sides of the machine.

Fig. 11 is a corresponding plan view.

Fig. 12 is an elevational view of a detail.

Fig. 13 is a general view as seen from above showing the automatic warp feeding means of the systems of weaving units forming the compound machine.

Fig. 14 is a corresponding elevational view.

Fig. 15 is a plan view showing the central signalling system indicating the stoppages of any kind whatever affecting any of the weaving units.

Fig. 16 is a corresponding elevational view.

Fig. 17 is a front view of a central signalling board.

Turning to Figs. 1 and 2 illustrating respectively, in plan view from above and in vertical elevational view, the compound weaving machine, it is apparent that the latter is constituted by the assembling into a compound machine of twenty producing elements that is of twenty elementary weaving units distributed into two groups arranged back to back, shown respectively at A and A₁ and including each ten elementary units.

To this purpose, the compound machine includes longitudinal beams, for example, four, one beam 1 being shown in the drawing, the beams extending throughout the length of the machine respectively in its lower part and its upper part. To these beams are secured end frames 3 and intermediary frames 4, each of the latter supporting different members forming part of the four adjacent weaving units, any two successive units arranged on the same side of the machine being provided to either side of the corresponding intermediary frame.

All the weaving units of the machine include means for the vertical upward beaming of the warp 5, 6 designating the warp beam located at the lower part of the unit and 7 the beam located at the upper part of the loom for the winding of the fabric produced 8.

As clearly apparent from Fig. 3, the warp 5 in each weaving unit winds off the beam 6 that

is suitably braked through any known means and it then passes over back rail rollers 9 and 10 (Fig. 3) adapted to carry the warp threads and between which the latter are constrained to move horizontally through the warp stop motion dropper 11, the roller 10 which is stationary for weaving certain articles, may be controlled mechanically so that it will rise to relieve warp tension. For that purpose the roller 10 may be rocked by a cam (not shown) mounted on a driving shaft, another roller (which is also not shown) being mounted on a lever in a manner which is well known. The warp threads pass also through horizontal heddles of harnesses 12 and 12' adapted to form shed and then through a substantially horizontal reed 13.

The fabric produced illustrated at 8 that is kept at its proper width by temples 14, is urged upwardly by a roller 15 and is wound over the cloth beam 7 that rises as the length of fabric increases inside the fork-shaped slides 16 secured to the upper end of the frame.

The harnesses 12 and 12' carried by horizontal slideways that are not illustrated are controlled through the agency of the levers 17 and 17' ending with rollers submitted to the action of eccentrics 18 and 18' arranged in diametrically opposed relationship and acting in antagonism with the springs 19 and 19'.

20 20 designates the shuttle travelling through the shed over the reed 13 that is slightly sloping towards the inside of the loom so that the shuttle may bear during its progression against a guiding wall 21, rigid with the reed and lined with velvet. The reed 13 (Fig. 3) of each elementary loom or unit is carried at its ends between the ends of two rocking slay arms or levers 22 (see also Fig. 5) whose opposite ends oscillate around spindles 23 under the action of cams 24 keyed to the main shaft 25 and which act on rollers 26 carried by said levers 22, the oscillations of which cause the reed 13 to raise so as to beat-up the weft. In Fig. 3, the reed of the elementary unit A on the front side of the machine is illustrated in its raised position, for which the weft is being urged against the fell of the cloth while the reed of the other elementary unit A₁ is in its lower stationary position for which the shuttle travels through the shed over said reed 13 that is, as stated, transiently stationary.

25 The control of the system of elementary units of the compound machine is provided through the upper common shaft 27 driven by an electric motor 27a, that may be located for instance at the end of the machine and transmits through belts 28 its movement to the individual driving pulleys 29 of the different elementary units.

With a view to reducing the bulk of the machine longitudinally, through a reduction in the spacing between the fabric sheets produced on one side of the compound machine, it is of advantage to associate two by two on a common support and in adjacent relationship the shuttle boxes of any two successive elementary units so as to provide for an overlapping of each unit with reference to the unit lying to either side thereof as readily apparent from inspection of Figs. 1, 2, 4 and 5.

30 30 Thus for instance, each of the two stationary shuttle boxes 30—30 of the weaving unit A illustrated in Fig. 5 is carried by the same support as the shuttle box 30a or 30b for the corresponding adjacent weaving units and to the front 75 thereof, each of said supports being secured

through its middle to the corresponding intermediary frame 4.

The reed 13 of the unit A in the center of Figure 5 is correspondingly shifted outwardly with reference to the reeds 13a and 13b of the adjacent individual units. This is the reason why Fig. 3 shows in addition to the shuttle operating in the shed illustrated as produced by the units A and A1, the shuttle corresponding to the adjacent units.

The throwing of the shuttles is produced in the example illustrated by under-pick motions including as well known a picker stick 31 to the upper end of which is secured a picker 32 adapted to drive the shuttle; at its lower end the picker stick 31 is secured to the shoe 33, the curvilinear lower surface of which bears against the upper horizontal surface of a carrier 34 whereby the picker 32 is adapted to assume a rectilinear path for driving the shuttle. The picking shaft 35 that is driven by the main shaft 25 as shown in Fig. 3, through the agency of the gearwheels 36 and 37 carries a platen 38 (Figs. 3 and 4) provided with a boss or projection 39 (Fig. 3); the latter acts on a roller 40 as shown in Fig. 4, carried by an arm 41 that acts in its turn through a pivoting linkage 42—43 on a member 44 rigid with the picker stick 31. The travel of the picker stick required for driving the shuttle is limited by an abutment 45 secured to the intermediary frame and the length of which is sufficient for it to cooperate with the picker sticks of the two adjacent units, which picker sticks are shifted in the same manner and by the same amount as the corresponding shuttle boxes. The return of each picker stick into its inoperative position is ensured by a belt 46 submitted to the action of a coil spring 47. It should be noted that there are two coil springs 47 arranged in different vertical planes (the medial plane of the two shuttle boxes), each coil driving a picker stick.

The automatic replacement of the weft is performed in each weaving unit through a change of cop or through a change of shuttle.

In the case of a cop-changing device (Figs. 6 and 7) the full cop or weft holder 48 that is held in position by the rocking cop-holding blade 60, is urged downwardly into the shuttle 49 and drives out of the latter the empty cop 50. The object of the blade 60 is to prevent the cop or weft holder 48 from falling into the shuttle box. When the cop or weft holder 48 is introduced into the shuttle by means of the piston 51, the blade 60 rocks downwardly and reverts to its initial position by means of a spring (not shown). This change of cops is obtained through the downward movement of a piston 51 rigid with two sliding rods 52 guided in the support 53. The rods 52 are connected through a stay 54 operatively engaging one arm of a forked lever 55 pivotally secured at 56 and the other arm of which carries a roller 57 controlled by a cam 58 keyed to the shaft 59 that receives its movement from the main shaft 25 and that is actuated when the weft stop motion or the weft feeler provides for a change of cops.

In order to provide for automatic feed, in lieu of the usual manually operated loading for the separate individual holders of the whole system of weaving units on one side of the machine, I have provided according to my invention means for feeding full cops to said holders and for removing the ejected exhausted cops.

These means consist, as illustrated, of two

horizontal conveyors 61 and 62 constituting preferably the upper and the lower strand of a common conveyor belt. The full cops 48³ laid longitudinally over the conveyor 61 appear at the upper end of the individual cop-holder 63. Such a cop 48³ (Fig. 6) enters the holder only if the blade 64 in the latter has been set in a position 64' as illustrated in dot and dash lines in Fig. 7, that is if it projects above the conveyor in a manner such that it constrains the cops to slide into the upper opening of the holder 63. This position 64' of the deflecting blade 64 is obtained when a change of cop being called for, the spare cop 48² has entered a position 48¹ inside the holder by reason of the original cop 48³ having replaced itself the cop or weft holder 48 laid into the shuttle. When such a cop 48² enters the position 48¹, it no longer bears against the controlling projection 65 the rocking of which is thus provided by gravity and controls the blades 64.

The exhausted cops 50 are ejected into the channel 66 wherein they are laid on the exhaust conveyor 62 which latter leads them into the collecting receiver 103 located at one end of the machine (Fig. 14).

The conveyor is constituted preferably by an endless belt stretched over two pulleys located each at one end of the machine. One of said pulleys is a driving pulley and receives a movement at a speed suiting the number of cops that are used for operation per unit of time.

This conveyor including the strands 61 and 62 is carried by a support 67 secured to the upper portion of the machine frame. The conveyor belt is carried by U-shaped beams 68 and 69 the lateral walls of which form guides for the cops that are being conveyed. At intervals, there are provided rollers 70 and 71 fitted in the U-shaped beam for carrying the conveyor strands.

Stays 72 provide for the carrying of the lower U-shaped beam 69 in a hanging position, said lower beam being secured furthermore to the individual ejection channels 66.

Should a change of shuttles be performed instead of a change of cops, the mechanism includes in an alternative embodiment (Figs. 8 and 9) a double storied box the front wall 73 of which is stationary while the horizontal plates 74 and 75 may rise and sink simultaneously and are rigid to this purpose with the vertical sliding rods 76 that are provided each with a stud 77 engaged by a fork 78 rockingly supported by the pivot 79 and extending beyond said pivot 79 to form an arm; the latter carries a roller 80 controlled by a cam 81 keyed to a shaft 82, the movement of which is controlled in its turn by that of the main shaft 25 and that is actuated when the weft stop motion or the weft feeler provides for a change of shuttle. The movement of the shaft 82 by the main shaft 25 is identical with the movement of the shaft 59 by means of the picking shaft 35.

The shuttle 83, the provision of weft thread 65 of which is exhausted, is located on the lower story of the box and the shuttle 84¹ that is to replace it is located on the upper story and a further spare shuttle 84² rests freely over said shuttle 84¹.

When a change of shuttle is provided the following operations are produced in succession:

The spare shuttle 84² is held fast against a stationary wall 85 by a buffer 86 that is submitted through the agency of a spring 87 to the thrust of a two-arm lever 88 adapted to rock round the

pivot 89 and controlled in its turn by a cam 90. The brake 91 for the exhausted shuttle 83 being released through any suitable means that are not illustrated, the two-storied shuttle box sinks so that the full shuttle 84 may come in front of the driving picker to replace the exhausted shuttle 83; the manner in which the two-storied shuttle box derives its sinking motion by means of the sliding rod 76, the stud 77, the fork 78, the roller 88, and the cam 81 has been described hereinabove; the latter lying in the lower story 74' is driven out by the ejector 92 constituted by two push members keyed to a horizontal spindle 93 receiving a pivotal movement through the agency of a rod 94 and a lever 95 controlled by the cam 96 through the agency of the roller 97 (Fig. 9). The exhausted shuttle 83 is thus removed.

The throwing of the new shuttle is performed, after which the two plates 74 and 75 rise. The buffer 86 releases the shuttle 84² that drops into the upper story of the shuttle box. The new shuttle that has been picked returns to the lower story of the shuttle box since the box has been elevated subsequent to picking.

In a manner similar to that already disclosed with reference to the change of cops, the full shuttles may be transferred through a conveyor belt 61 and the empty exhausted shuttle may be removed through a conveyor belt 62. For executing the automatic replacement of the spare shuttle 84², I use a deflecting blade 98 carried at the end of one of the arms of a lever 99 pivotally secured at 100. The end of the other arm carries a feeler 101 (Fig. 9) that is normally urged back by the spare shuttle 84² and leaves then the blade 98 in its retracted position, while said feeler-carrying end produces on the contrary, under the action of a spring whenever the shuttle 84² has been removed, a pivoting movement of the lever 99 whereby the blade 98 assumes with reference to the conveyor 61 the position illustrated in dot and dash lines at 98' in Fig. 9, which allows the admission of a shuttle that slides through a channel 126 and arrives into the shuttle box in which it occupies the position 84². The dropping of the exhausted shuttles 83 on to the conveyor 62 providing for their removal is guided through the channel 102.

As concerns the feeding of the conveyor 61 with cops or shuttles, as the case may be, it is performed preferably in an automatic manner by means of an arrangement forming a general holder and distributor and located at one end of the compound loom.

Such an operation is illustrated by way of example in Figs. 10 to 12 for the case where the change of weft is provided through a change of cops.

The cops or weft holders 48 are housed inside a holder 104 constituted by a sloping channel opening above the conveyor 61 (Figs. 13 and 14) and the shape of the transversal cross-section of which is illustrated in interrupted lines in Fig. 11; the ends of the thread of the different cops are tensioned and are secured to a strip 105 carrying said ends, said strip being somewhat similar to a card clothing. Said strip is stretched under the form of an endless band between two rollers 106 and 107 (Fig. 11) of which one 106 is rigid with a ratchet wheel 108 through the agency of which a forward movement is given to the strip 105 each time a cop is being distributed. In register with the lower open end of the channel-shaped holder 104 is provided a blade 109 against 75 of arrangement 108

which is held the cop arriving in front of the opening in the holder. The blade 109 that may pivot round a spindle 110 carried in bearings rigid with the support 67 (Figs. 10 and 11) carries a roller 111 raised at the suitable moment by one of the cams 112 (Fig. 11) secured to the conveyor 61. On the spindle 110 also carried by the support 67 is fitted a hub 114 for a two-arm rocking lever 115—115a. The arm 115a carries a roller 116 adapted to be raised at a suitable moment by one of the cams 112 on the conveyor, so as to constrain the arm 115 to rock downwardly, said arm ending with a catch or tooth 117 adapted to engage the ratchet wheel 108. The arm 115 carries furthermore a projection 118 for controlling at the moment of its rocking the downward movement of the movable arm 119 of scissors adapted to cut the thread at the output end of the cops. Lastly the same arm 115 carries a buffer 120 submitted to the action of a torsional spring 121 and adapted to exert a pressure on the cut end of the thread passing out of the cop that is being delivered by the conveyor 61, whereby said end of the thread engages a reed-shaped member 122 secured to said conveyor and constituted by a fragment of card clothing.

Considering for instance the cam 112¹ (Fig. 11), its passage under the roller 111 of the blade 109 will produce a rising movement of the latter and consequently constrain a cop 48 or weft holder to drop into the position 48¹ as a consequence of the transient receding movement of said blade 109. The same cam 112¹ passes then underneath the roller 116 of the rocking lever 115a and produces on one hand the engagement of the weft thread with the card clothing reed 122 and on the other hand the cutting of the thread by the thread-cutting scissors 119 and furthermore it operates an angular rotation of the ratchet 108 through the catch 117 so as to make the strip 105 carrying the thread ends advance by the desired amount.

A similar arrangement may be provided for distributing the shuttles on the conveyor in the case of a shuttle changing device being used.

As for the centralised signalling provided through the compound machine according to my invention and that is illustrated in Figs. 15, 16 and 17, it is apparent that, in addition to the usual arrangements 123 mounted in each elementary unit and indicating the stoppages arising through the warp or through the weft or through mechanical mishaps, it is possible to provide at the end of each weaving machine a centralising board 124 on which are signalled the different mishaps arising in the elementary units on either side of the machine. Each arrangement 123 is a device consisting of signal lamps of different colors, corresponding to the stoppages. For instance, a red lamp is preferably provided for stoppages occurring when the warp is broken, a green lamp for stoppages occurring when the weft is broken, a white lamp for other stoppages, for example, when a shuttle does not properly enter its box or remains in the shed. On panel 124 (Fig. 17), the same colors for each weaving units are shown as on the respective separate arrangements 123. For instance, the three reference numbers 1 on one of the half-panels correspond, respectively, to small windows provided with red, green, and ordinary glasses and the lights behind said windows are lighted at the same time as the respective lights of arrangement 123 of the corresponding weav-

ing units. In Fig. 17, the digits 1, 2 . . . 10 correspond each to one of the units and the three identical members recorded on the board 124 for the unit considered appear for instance in gates cut in the board and provided with glasses of different colors, according to the nature of the mishap that is signalled and that produces the illumination of the corresponding gate. On panel 124 (Fig. 17), the same colors for each weaving unit are shown as on the respective 10 separate arrangement 123. For instance, the three reference numbers 1 on one of the half-panels correspond respectively to small windows, provided with red, green, and ordinary glasses and the lights behind said windows are lighted at the same time as the respective lights of arrangement 123 of the corresponding weaving unit. A watchman positioned at 125 may thus inspect four double panels 124 corresponding in the case illustrated to eighty weaving units 20 forming four compound weaving machines.

It should be remarked that the centralised design of a compound machine allows associating therewith a centralised automatic lubricating system constituted by an arrangement similar to those used on automobile vehicles.

Obviously, my invention is by no means limited to the embodiments disclosed hereinabove and many modifications or detail improvements may be imagined and equivalent means may be used for those described without unduly widening thereby the scope of the invention as defined in accompanying claims. For instance, the elementary weaving units may be of the type wherein the weft is fed continuously through large stationary spools and weft inserters.

What I claim is:

1. In a weaving machine having a plurality of independent elementary weaving units, a main frame comprising at least two longitudinal beams extended along the whole length of the machine, a plurality of transverse frames secured to said longitudinal beams, each frame being adapted to support four elementary weaving units arranged in two couples back to back, the units of each said 45

couple being respectively secured on each side of said transverse frame.

2. A weaving machine comprising two series of aligned elementary weaving units arranged side by side, the elementary units in the two series being arranged back to back, each unit including a vertically reciprocating horizontal reed, stationary shuttle-boxes, means adapted to throw a shuttle between the shuttle-boxes over said horizontal reed when in its lowermost position, means for feeding the warp to form a shed to either side of the reed and means for raising periodically the reed after each pick insertion, and a frame to which the different elementary weaving units are rigidly secured, the corresponding stationary shuttle boxes on the adjacent elementary weaving units being secured to said frame, and the shuttle boxes of the odd units in each series being laterally shifted with reference to those of the even numbered elementary weaving units for producing an overlapping between the warp sheets of the successive elementary units.

3. The combination of claim 1, wherein each 25 transverse frame carries four shuttle boxes, the two outside boxes being arranged to be used for the two weaving units on one side of the transverse frame, the two inner boxes being arranged to be used for the two weaving units on the other side of said frame, the reeds of the weaving units on one side of said frame being transversely shifted with respect to the reeds of the units mounted on the other side of said frame.
